UNITED STATES PATENT OFFICE.

CARL OTTO LANDGREBE, OF DRESDEN-A., GERMANY.

SPARK-PLUG SERVING ALSO AS COMPRESSION AND INJECTION VALVE FOR INTERNAL-COMBUSTION ENGINES.

1,401,612.

Specification of Letters Patent. Patented Dec. 27, 1921.

Application filed May 28, 1917. Serial No. 171,552.

(GRANTED UNDER THE PROVISIONS OF THE ACT OF MARCH 3, 1921, 41 STAT. L. 1313.)

To all whom it may concern:

Be it known that I, CARL OTTO LANDGREBE, a subject of the King of Prussia, residing at Dresden-A., Saxony, Germany, have invented certain new and useful Improvements in Spark-Plugs Serving Also as Compression and Injection Valves for Internal-Combustion Engines, of which the following is a specification.

10 My invention relates to spark-plugs which also serve as compression and injection valves for internal combustion engines, and a primary object is to provide an improved device of the type described in which, in contradistinction to those known heretofore, the lower pointed end of the valve spindle suitably insulated from the casing is automatically seated upon the sharp-edged seat under the action of a spring and thereby closes the 20 valve, one of the electrodes being carried by the spindle and the other constituted by the casing of the valve.

As compared with known spark-plugs or with known compression and injection valves, my improved device has a number of advantages, of which the following may be mentioned. Firstly, the valve is closed automatically by means of a spiral spring which constantly tends to turn the threaded spindle 30 in the required direction. Consequently, mistakes in the operation of the valve cannot occur. Secondly, owing to the end of the spindle being formed as a needle valve and being seated on the sharp edges of the 35 seat, a reliable tight closure is effected, and as the seat is located near the spark-gap, the interior of the spark-plug does not heat and it is impossible for the insulation to crack. Consequently, the long channels or ducts

40 which are subject to explosions and are readily fouled in devices of the type in question known heretofore, are obviated in my improved device. Further, the improved device enables benzine, petroleum or the like 45 to be readily injected and the electrodes to be cleaned thereby, and it is consequently no longer necessary, as formerly, to screw out the valve-spindle for this purpose. Another advantage is that when the valve is fully 50 open no spark can pass, and, lastly, unintentional changes in the length of the spark-gap cannot be made.

To these ends, the invention consists in the

construction, arrangement and combination of parts described hereinafter and pointed out in the claim.

One illustrative embodiment of the invention and a modification thereof are represented by way of example in the accompanying drawing, wherein:

Figure 1 is a vertical section showing one form of the improved device, and

Fig. 2 is a like view of a modified form.

Referring to Fig. 1, the spark-plug constituting also a compression and injection valve can be screwed into the cylinder of an engine by means of the internally-threaded casing *a* shaped like a nut. A tapered nut *b* of the form clearly shown in section in the drawing is screwed into the casing *a* and holds the insulation *c* firmly in position against a fitting or conical member *d* which is thereby also held in position; the members *b*, *c*, *d* are firmly held together by means of a nut *e* which is screwed on the member *d* and presses on the ring *f* of insulation placed on the top of the nut *b*. The member *d* has an internal thread, into which is screwed the threaded valve-spindle *g*, the lower end of which is conical and constitutes 80 the valve-disk which is normally seated on the sharp edge of the opening *h* in the bottom of the member *d* and thus effects a reliable tight closure.

A spiral spring *i* is arranged in such a manner at the upper end of the valve-spindle *g*, that it constantly tends to turn the latter into its closed position.

The lower conical end of the spindle *g* constituting the valve-disk carries a pin *k* 90 of suitable material which forms the one electrode. The other electrode is constituted by the bottom of the casing *a* which may be notched or provided with radial points, not shown.

95 The spindle *g* is provided with a longitudinal bore hole *l* and with a transverse hole *m* connected therewith, the bore *l* running out at the top into a funnel *r*, through which benzine or the like can be introduced. 100 The electric cable (not shown) is suitably connected to the nut *e*, or is suitably directly electrically connected to the spindle *g*, and the current passes down the spindle *g* to the electrode *k* and jumps in the form of a spark, 105 across the gap to the casing *a*.

A hand lever *s* serves for turning the spindle *g* and opening thereby the valve.

As the benzin passes the electrodes on its being injected through the channels *l*, *m* when the spindle *g* is turned and the valve opened, the spark-gap is cleaned in a very simple manner.

In the modified form of the device shown in Fig. 2 the funnel *r* is arranged laterally on the casing *a* in such a manner that the channels *l* and *m* are obviated, the funnel in this modification being connected by a duct *n* with a space or chamber *o* located between the valve-spindle *g* and the member *d*. Otherwise the arrangement and mode of operation of this form are the same as those of the device described above with reference to Fig. 1.

I claim:—

A spark plug including an outer casing 20 provided with an internally threaded opening forming a valve seat at its lower end, and a central hollow electrode provided with a valve at its lower end adapted to be positioned within said opening, the valve being 25 adapted to seat upon the rotation of the electrode within the opening by reason of the latter's engagement with the screw threads.

In testimony whereof I have hereunto set 30 my hand in presence of two subscribing witnesses.

CARL OTTO LANDGREBE.
